UNITED STATES PATENT OFFICE.

WILLIAM GUÈRIN, OF LIMOGES, FRANCE.

DESIGN FOR A COVERED DISH.

SPECIFICATION forming part of Design No. 22,421, dated May 9, 1893.

Application filed April 5, 1893. Serial No. 469,234. Term of patent 7 years.

To all whom it may concern:

Be it known that I, WILLIAM GUÈRIN, a citizen of France, residing at Limoges, in the Department of Haute-Vienne and Republic of France, have invented and produced a new and original Design for Dishes; and I do hereby declare the following to be a full, clear, and exact description of the same, reference being had to the accompanying drawings forming a part thereof.

The leading feature of my design consists of a low oval dish having scroll-like or rococo handles, and irregular or scalloped configurations; the cover and dish being marked by several indented scroll-like divisions.

Figure I represents a plan view of the dish cover; Fig. II a side view of the dish, these two views being deemed necessary to fully illustrate my design.

In Fig. I A represents the scroll-like handle rising irregularly from points near the center of the cover, and forming an ornamented arch or volution. The edges of the cover B, and

dish C follow the configuration of the irregular scallops. These irregular scallops mark indentations D in the body of the dish and cover. The handles E on the body of the dish spring from points at opposite ends so as to pass over one of these indentations in ornamental curves. The base of the dish F and the periphery of the cover f. are ornamented with irregular scroll-like scallops.

Fig. I gives a face view of the cover with the handle ornamented at the point where it joins the cover with scroll work extending toward either end.

What I claim is—

A design for a dish substantially as described and shown.

In testimony whereof I affix my signature in presence of two witnesses.

W. GUÈRIN.
